Application October 19, 1937, Serial No. 169,808

5 Claims. (Cl. 22—68)

This invention relates to casting presses of the type in which a casting material is injected in liquid form, such as molten metal, into suitable dies, the sections of which are separable to remove the cast articles. A press of this type is particularly useful in the production of magnesium castings, and the like.

One object of the invention is to generally improve presses of this type.

Another object of the invention is to provide an improved casting press, with which the point of injection of the casting material into the dies may be varied to some extent for different types of jobs, with which the castings may be produced with a minimum of "flash" at the junctions between the die sections, with which the castings may be ejected or loosened in the dies in a simple manner, automatically, upon the separation of the die sections, and which will be relatively simple, convenient, rapid in operation and inexpensive.

Another object of the invention is to provide an improved casting press, with which an accumulator may be used as the source of power for producing the injection of the liquid casting material into the dies in order to obtain maximum speed of injection, with which the die sections may be closed and held together in a simple, rapid and practical manner, with which the injection of the casting liquid may be effectively prevented until the pressure holding the die sections together exceeds a predetermined minimum pressure, and with which the separation of the die sections under the injection pressure will be reduced to a minimum and substantially prevented, with consequent reduction in the formation of "flash" on the castings at the junction between the die sections.

Other objects and advantages will be apparent from the following description of an embodiment of the invention, and the novel features will be particularly pointed out hereinafter in connection with the appended claims.

In the accompanying drawings:

Fig. 1 is a side elevation of a metal casting press constructed in accordance with this invention;

Fig. 2 is a plan of the same;

Fig. 3 is a longitudinal sectional elevation through the same, with intermediate portions removed and the injection cylinder broken off in order to reduce the over-all length of the figure;

Fig. 4 is an elevation of a portion of the same, the view being taken approximately along the line 4—4 of Fig. 3 to show the end of the injection device and its engagement with the pressure head by which limited adjustment of the injection device may be obtained;

Fig. 5 is a sectional plan of the interlock for

the press, the section being taken approximately along the line 5—5 of Fig. 1;

Fig. 6 is a transverse sectional elevation through the interlock, the section being taken approximately along the line 6—6 of Fig. 5;

Fig. 7 is a view similar to Fig. 6, but with the parts in a different operative position, such as when the pressure holding the die sections together is sufficiently high so that it is safe to cause an injection of the casting material into the die sections;

Fig. 8 is another sectional elevation through the interlock, the section being taken approximately along the line 8—8 of Fig. 5;

Fig. 9 is a view of a portion of Fig. 8, but with the parts in the positions taken during the injection of the casting material or metal into the die sections; and

Fig. 10 is a schematic diagram illustrating the controls for the press and the manner in which the interlock functions.

In the illustrated embodiment of the invention the improved casting press is illustrated as of the type utilized for the production of metal castings and particularly for the production of magnesium castings. The improved press includes a main base 10 with a pressure head 11 extending uprightly therefrom. A ram base 12 is secured in any suitable manner to the main base 10, but is illustrated as adjustable along the main base 10 and may be suitably anchored in different adjusted positions. This ram base 12 contains a ram cylinder 13, Figs. 1 and 3, in which a main ram 14 reciprocates as usual in hydraulic presses. Secured to the outer end of the ram 14 is a platen 15 which is reciprocated toward and from the pressure head 11 in a manner common in hydraulic presses.

Complementary die sections 16 and 17 are secured to the platen 15 and pressure head 11 respectively, and when these die sections are brought together in abutting face to face relation they form a die in which the casting occurs. These die sections are secured to the opposing faces of the head 11 and the platen 15 in any suitable manner such as is common in the mounting of dies on hydraulic presses or in casting presses. The die section 17, which is secured to the pressure head, is provided with an inlet passage or gate 18 which is in communication with one end of a chamber 19 in an injection cylinder or device 20. The cylinder 20 passes through a vertically elongated slot 21 in the pressure head 11, and at an end abuts the die section 17 by means of a peripherally flanged head 22 which is countersunk into the adjacent face of the pressure head 11, such as into a groove 23 bordering the slot 21, so that the flange definitely prevents the cylinder or shell 20 from being forced endwise through the pressure head 11.

11 and away from die section 17 by the reaction of the casting materials forced into the die sections.

In the form illustrated, the cylinder or shell 5 20 is tubular with a chamber or passage 19 that runs from end to end therethrough and is preferably cylindrical in shape. The gate or passage 18 in the die section 17 opens into the chamber 19 at the upper edge thereof, so that when the 10 liquid casting material or molten metal is placed in the chamber 19, preparatory to injection into the die sections, it will remain within the passage 19 until forced out in a manner to be explained presently and will not drain out preliminarily through the gate 18. Reciprocating in 15 the outer end of the chamber 19 is an injection plunger 24 which is connected at its outer end to a yoke 25. The yoke 25 in turn is connected to a piston 26 which reciprocates in one end of a 20 ram cylinder 27. The yoke 25 reciprocates on sleeves 28 which are provided on strain rods 29 that tie a laterally extending anchorage block 30 on the cylinder 27 to the pressure head 11.

The pressure head 11 is provided with undercut, vertically extending slots 31 in which flanged ends or heads 32 of the strain rods are received, with the shanks of the rods passing through the faces of the slots and with the heads 32 running in the undercut portions of the slots. The block 30 is supported through a plurality of separate, removable shim plates 33 upon a bracket arm 34 projecting upwardly from the main base 10. By varying the number of shim plates 33 between the bracket 34 and the anchorage block 30 of the cylinder 27, the cylinder 27 may be adjusted vertically to different extents, and by loosening the strain rods, they may be also adjusted vertically through a sliding of the heads 32 along the slots 31 so as to set the metal injection device and its actuating elements in different adjusted levels or positions above the base 10. Thus the injection passage 19 may communicate with a gate 18 selectively placed at different heights above the base 10 as may be necessary for different types of casting jobs. The cylinder 20 of course moves vertically with the vertical adjustment of strain rods 29 and cylinder 27, such adjustment being possible by reason of the vertically elongated slot 21.

The cylinder 20 has a charging opening 35 in its upper wall immediately in front of the inner end of the injection plunger 24 when the latter is in its outer or retracted position, as shown clearly in Fig. 3. Thus, when an actuating pressure is applied to the cylinder 27 in a direction tending to eject the ram piston 26 therefrom, the yoke 25 will be operated toward the head 11 and thus the injection ram 24 will be forced along the passage or chamber 19 so as to eject therefrom and through the gate 18 into the die sections, a liquid casting material which has previously been placed in the chamber or passage 19. Thus at the start of each operation, the liquid casting material or metal is poured into the chamber or passage 19 through the charging opening 35, and then the reciprocation of the plunger 24 will force this casting material through the gate 18 into the die sections, after which the plunger 24 is retracted by a reverse operation of the ram piston 26.

The cylinder 27 and piston 26 together form a double action hydraulic ram and, as such hydraulic rams are well known in the art, they need little description. The end piston 26, which 75 is within the cylinder 27, is provided with a pis-

ton head engaging with the inner wall of the cylinder, and thus the piston may be reciprocated in one direction or the other, depending upon the end of the cylinder 27 to which the actuating liquid is supplied.

A pipe 36 extends to the outer end of the cylinder 27 so as to supply an actuating liquid tending to force the piston 26 to the left in Figs. 1 to 3, and cause an injection of casting material into the die section. The piston 26 is retracted by liquid admitted to the cylinder 27 at the other end through a pipe 37 which opens into the cylinder at the anchorage block 30.

The piston 14 which reciprocates in the cylinder 13 forms with the cylinder 13 a double-acting type of ram which positively advances and retracts the platen 15. The end of the piston 14 within the cylinder 13 is provided with a piston head 38, Fig. 3, which may have piston rings 39 acting between its periphery and the inner wall of the cylinder 13. The outer end of the cylinder 13, through which the piston 14 passes, is normally closed by a suitable packing gland or device 40, as usual in hydraulic rams. The inner end of the piston 14 is provided with an annular recess 41 which telescopes over a tubular flange 42 projecting axially of the cylinder from an anchorage base secured to the inner end wall of the cylinder in any suitable manner. The central stem of the piston 14 which telescopes within the flange 42 may also be provided with a piston head 43. A pipe 44 opens through the end of the cylinder 13 into the space within the annular flange 42, and another pipe 45 opens through the end of the cylinder 13 into the space around the outside of the annular flange 42.

The platen 15 is provided with a vertically extending cavity or passage 46 in which is loosely mounted a knock-out bar 47. Work-ejecting pins 48 extend through the platen 15 from the knock-out bar 47 into the die section 16. Knock-out pins 49 extend from the knock-out bar 47 through the platen 15 towards the ram base 12 and into position to engage against the base 12 when the platen is retracted into the position shown in Fig. 3. When the platen advances into die-closing position, the knock-out bar 47 and knock-out pins 49 will move with it, and the pressure of the injected casting material within the die sections will force the pins 48 in a direction out of the die sections 16, and thus will force the knock-out bar 47 rearwardly. This, in turn, will force the knock-out pins 49 rearwardly to a corresponding extent. When the knock-out bar 47 is in its rearmost position, that is, abutting the side wall of the slot 46 nearest the cylinder 13, the ends of the ejecting pins 48 will be flush with the inner wall of the die cavities in the section 16. Other means, such as springs, may also be used to urge the bar 47 and pins 48 and 49 towards the cylinder 13. After each casting operation, the platen 15 is retracted, and as it approaches its retracted position, the pins 49 will engage with the ram base 12 and be moved endwise so as to shift the knock-out bar 47 horizontally across the slot 46, and this will in turn force the pins 48 into the cavity of the die section 16 and thus loosen or eject the work or castings from the die section 16.

Referring now to the schematic diagram shown in Fig. 10, the manner in which the activities of the pistons 14 and 26 are controlled will be described. The pipe 44 which leads to the cylinder within the flange 42 is connected to a port 50 in the casing 51 of a manually operated four-way

valve. In the casing 51 is a spool-shaped valve element 52 which reciprocates along the cylinder 51. One flange of the spool is adapted to cover and close the port 50 when the element 52 is in an intermediate position, and to uncover it when shifted into the end positions at opposite sides thereof. A continuously operating, variable delivery type of pump 53 is connected at its intake side through a pipe 54 to a reservoir 55 from which it withdraws operating liquid, and at its outward side the pump 53 is connected by a pipe 56 to a port 57 in the valve casing 51 at a point between the flanges of the spool-shaped valve element 52. A branch of the pipe 56 also extends to the cylinder 13 at the end adjacent the gland 40.

The flange 58 of the valve element 52 which covers the port 50 is cylindrical in shape, so that when it is in alignment with the port 50 it effectively closes that port, but the other flange 59 of the valve element 52 is provided at its periphery with oppositely bevelled faces 60. The inner wall of the casing 51, in alignment with the bevelled flange 59 when the flange 58 closes the port 50, is provided with an annular groove 61, and a pipe 62 leads from the annular groove 61 to the pilot cylinder 63 of a pilot-operated check valve 64. The cylinder 51, at its ends, is provided with exhaust ports 65 and 66 which are connected by a pipe 67 to the tank 55. Thus, the operating liquid withdrawn from the tank or reservoir 55 through the pipe 54 by the pump 53, will be delivered through the pipe 56 partly to the outer end of the cylinder 13 and partly to the port 57, and thence to the space between the flanges of the spool-shaped valve element 52.

The valve element 52 is shown in Fig. 10 as in its intermediate position, and it may be shifted in either direction therefrom by means of a lever 68 which is pivoted at 69 to the valve casing 51. At an intermediate point, the lever 68 is connected by a lost motion connection, such as a pin and slot connection, indicated by the reference 70, to a stem 71 projecting from the valve element 52 outwardly through a suitable packing gland 72 in the valve casing 51. Suitable means such as a spring-operated detent 73 that engages in notches 74 provided along the stem 71, is employed for releasably locking the valve element 52 in any of its three positions of reciprocation in the valve casing 51. The pipe 45 which leads to the closed end of the cylinder 13 exteriorly of the flange 42 is connected to the check valve 64, and this check valve 64 is also connected by pipe 74 to the reservoir or tank 55. With the valve element 52 in the intermediate position shown in Fig. 10, and with the pump 53 operating, the liquid from the pump 53 will be conducted through the pipe 56 to the outer end of the cylinder 13 and also to the port 57 of the valve casing 51.

From the port 57 the liquid may pass around the bevelled flange 59 of the valve element 52 and thence through port 66 and pipe 67 back to the tank 55. Because of this free passage back to the tank 55, there will be no substantial pressure on the liquid delivered by the pump, and consequently no material pressure will be exerted on the piston 14 of the ram through any liquid delivered to the outer end of the cylinder 13. The check valve 64 is a freely closing check valve opening to pass liquid towards the cylinder 13, but it may be forcibly opened also when liquid is delivered under pressure to the pilot cylinder 63.

This type of check valve is disclosed, for exam-

ple, in United States Patent No. 1,765,627 issued June 24, 1930, to Thomas F. Stacy, to which reference may be had for a more complete disclosure. There will be no material pressure in the pipe 62 or pilot cylinder 63, at this time, because they are open to the port 66 leading back to the tank 55. The flange 58 of the valve element 52 closes the port 50, and thus escape of liquid from the cylinder 13 within the flange 42 by means of pipe 44 is effectively prevented.

The piston 14, therefore, remains in idle, retracted position, and the pump operates to circulate the operating liquid idly through the valve casing 51. To initiate a forward movement of the piston 14, the detent 73 is retracted and the valve handle 68 depressed, which shifts the valve element 52 downwardly in Fig. 10 until the flange 58 uncovers the port 50 and the bevelled flange 59 moves out of alignment with the groove 61 and occupies a position between the groove 61 and the inlet port 57. This interrupts communication between the ports 57 and 66, so that the liquid delivered by the pump can no longer pass idly back to the tank 55 through the pipe 67. The delivered liquid entering the casing 51 through the port 57 will thus pass through the port 50 and pipe 44 to the closed end of the cylinder 13 within the flange 42, and will there exert a pressure on the small piston head 43, which is a reduced projection of the piston 14. The pipe 62 will remain in communication with the port 66 and thus no pressure will be exerted on the pilot cylinder 63, and the check valve 64 will remain a freely operating check valve.

Some of the liquid delivered by the pump will also pass through the pipe 56 to the outer end of the cylinder 13 and it will exert in the peripheral chamber around the piston 14 and against the head 38 a pressure tending to force the piston 14 into the cylinder 13, while at the same time the liquid delivered through the pipe 44 to the closed end of the cylinder 13 will exert on the section 43 of the piston 14 a force tending to move the piston 14 outwardly of the cylinder 13. The end area of the section 43 of the piston 14 is greater than the annular area exposed on the head 38 facing that end of the cylinder 13 through which the piston 14 extends, and thus the pressure differential on piston 14 will force it outwardly and cause an advancing movement of the platen 15. As the piston 14 advances, it will tend to create a suction at the closed end of the cylinder 13 exteriorly of the flange 42, and this suction will be communicated through the pipe 45 to the check valve 64, whereupon the valve element 64a thereof will open freely and allow liquid to be drawn by suction from the tank 55 through the pipe 74, the check valve 64 and pipe 45, into the closed end of the cylinder to fill the space exteriorly of flange 42 which is vacated by the advancing piston 14.

This provides a relatively rapid advance for the platen 15, but just as the die sections are about to close with one another, a rod 75 adjustably carried by the platen 15 will engage and operate a valve 76. For example, the rod 75 may be provided with a head or flange 77 which engages with one of the arms of a forked handle 78 of the rotary valve element 79 of the valve 76, and rotates the valve element in a direction to connect the pipe 44 to the pipe 45. The liquid delivered through the pipe 44 will now divide and part of it will pass through the valve 76 and pipe 45 to the closed end of the cylinder exteriorly of the flange 43, so that the liquid delivered under 75

pressure by the pump will now be exerted on the entire end of the piston 14 at the closed end of the cylinder 13. When this happens, the pressure on the liquid in pipe 45 automatically closes the valve element 64a of the check valve 64 to prevent direct return through the pipe 14 of any of this delivered liquid. The platen 15 will then have continued movement in the same direction but at a slower rate, because of the fact that the operating liquid delivered through the pipe 44 must now be spread over a greater piston area. When the die sections meet, the resistance will mount rapidly and build up the holding pressure on the die sections.

The pump illustrated is of the continuously operating, variable delivery type, which automatically sets itself to approximately neutral delivery when the pressure on the piston 14 reaches or exceeds a predetermined minimum pressure. Such pumps are well known in the art and are disclosed, for example, in United States Patents Nos. 1,578,233 and 1,077,979. In this type of pump the rate of delivery is varied by shifting a yoke 80, and this yoke may be shifted by a lever 81 which is pivoted at 82 to a suitable part of the motor frame. The lever 81 is also connected by a pivot pin 83 to a link 84 which has a flange 85 at its free end. A rod 86 passes slidably through an aperture in the flange 85 and carries at one end thereof a shoulder or head 87. A spring 88 is provided on the rod 86 under compression between the head 87 and the flange 85, so as to urge the lever 81 in a clockwise direction in Fig. 10. The rod 86 passes slidably through a flange 89 of the motor frame, and is there threaded and provided with a hand wheel nut 90. Thus, by turning the wheel or nut 90, the rod 86 may be drawn through the flange 89 to different extents, and thus the pressure on the spring 88 varied.

The spring 88, acting through the link 84, tends to rock the yoke lever 81 in a clockwise direction, Fig. 10, and thus shift the yoke 80 in a direction to provide for maximum delivery of the pump. An auxiliary or delivery control cylinder 91 is also provided on the pump frame and a small ram 92 reciprocating in the cylinder 91 extends outwardly into abutting relation with the yoke lever 81 in a manner to oppose such clockwise movement of the lever 81 as is caused by the spring 88. A pipe 93 connects the other end of the cylinder 91 with the pipe 45 which leads to the closed end of the cylinder exteriorly of the flange 42. Thus, when the pressure on the piston 14 builds up after the die sections have closed, this rapidly increasing pressure is transmitted through the pipe 93 to the cylinder 91 of the pump, and when the pressure is sufficient to overcome the spring 88, the piston 92 will be forced outwardly to some extent and will rock the yoke lever 81 counter-clockwise in Fig. 10, and shift the yoke 80 in a direction to cut down the rate of delivery of the pump 53.

As the pressure continues to mount, the rate of delivery of the pump will be further cut down, and when the maximum pressure determined by the spring 88 is reached, the pump will have been set approximately to neutral delivery condition. Thus, the pressure will be maintained automatically because if, through leakage, the pressure on the piston 14 should fall to any appreciable extent, the plunger 92 will release the yoke lever 81 and the spring 88 will shift the yoke 80 in a direction to increase the delivery of the pump until the pressure has again been built up on the piston 14. Any slippage of liquid in the pump may drain

back to the tank 55 through the pipe 94. The pump will maintain this maximum pressure on the piston 14 and thus on the platen to hold the die sections closed as long as desired, which will be until the casting material has been injected into the die sections. The operator then sets the valve element 52 to cause a retraction of the platen 15. To do this the spring detent 73 is first retracted and the valve lever 68 is then shifted in the opposite direction through the neutral or intermediate position shown in full lines in Fig. 10 to a position in which the flange 58 is above the port 50 and the flange 59 of the valve element 52 is between the groove 61 and the port 66. The spring actuated detent 73 then latches the valve element 52 in that position.

When the valve element 52 is in this position, the port 50 will be connected through the lower end of the valve casing 51 with the port 65, and liquid may then pass from the closed end of the cylinder 13 within the flange 42 through the pipe 44, valve casing 51 and pipe 67 back to the tank 55. The liquid in the closed end of the cylinder 13 exteriorly of the flange 42 may pass through the pipe 45, valve 76 and pipe 44 also back to the tank 55. When this pressure falls, the continuing pressure on the opposite side of the piston head 38 caused by the continued delivery of liquid from the pump through the pipe 56 to the outer end of cylinder 13 will cause retraction of the piston 14 into the cylinder 13. At the same time, some of the operating liquid under pressure delivered to the pipe 56 by the pump, which of course continues to operate, will also pass through the valve casing 51 from port 57 to the groove 61 and thence through pipe 62 to the pilot cylinder 63. This liquid under pressure will then exert a pressure on the pilot cylinder 63, tending to forcibly open the free check valve element 64a, but this valve cannot open until the pressure in pipe 45 has fallen sufficiently, but such pressure will fall through escape of liquid from the pipe 45 through the valve 76 and pipe 44.

As soon as the pressure has fallen sufficiently to enable the check valve element 64a to be opened, the liquid from the pipe 45 may then pass through pipe 14 directly back to the tank 55 instead of through the valve casing 51. Early in the return movement of the platen 15, the head 77 of rod 75 on the platen will engage the other of the arms of the forked operating handle 78 of the valve 76, and will rock the valve element 79 into closed position as shown in full lines in Fig. 10, thus shutting off direct communication between the pipes 44 and 45. Both pipes 44 and 45 will however drain back into the tank 55 so that the continued pressure on the piston 14 tending to retract it into the cylinder 13 will continue the retraction of the platen. As the platen approaches its fully retracted position the knock-out pins 49 will engage the ram base 12 and through the knock-out bar 47 and work ejecting pins 48 will loosen the casting or castings from the die section 16. At this time the operator should retract the detent 73 and shift the valve handle 68 back into the position shown in full lines in Fig. 10 which sets the valve for idle circulation of the liquid from the pump 53. When this happens the pressure in pilot cylinder 63 will be released, and the check valve 64a will close. The platen 15 will then remain in this position until the valve handle 68 is again manipulated to start a forward or advancing movement of the platen 15.

The operation of the ram to inject the casting

75

liquid into the dies will now be described through continued reference to Fig. 10. The inner end of the piston 26 is provided with a piston head 95. The pipes 36 and 37 are connected to the cylinder 27 at opposite ends thereof which are at opposite sides of the piston head 95. The pipes 36 and 37 lead to intermediate ports of a pilot operated, fourway valve 96 having a spool shaped valve element 97 reciprocating endwise therein. The flanges 98 and 99 of the valve element 97 occupy one extreme position, as shown by the full lines in Fig. 10, which is the maximum position to the left in that figure. A pipe 100 connects the interior of the casing 96, at points spaced along the same substantially beyond the openings from pipes 36 and 37, with a tank 101 which may advantageously be the tank 55 when the same kind of liquid is used for operating both pistons 14 and 26, otherwise they are separate tanks.

Instead of a pump for supplying the operating liquid for the cylinder 27, we prefer to use an accumulator to supply the necessary operating pressure, because an accumulator maintains the same uniform pressure and provides for a very rapid delivery of the operating liquid under this maximum and uniform pressure. The accumulator 102 is of any suitable and well known type, and since accumulators are well known in the industry, a detailed description is omitted. In principle, an accumulator includes a weight-operated piston 103 which exerts a pressure on the liquid in the chamber 104, and the liquid so compressed, is conducted from the accumulator by a pipe 105, one branch 105a being connected to the valve casing 96 approximately midway between the openings of the pipes 36 and 37 into the casing 96. The other branch 105b of pipe 105 is connected to a pilot control valve 106 which will be explained presently.

Within the casing 106 is a spool-shaped valve element 107 having flanges 108 and 109 thereon. The pipe 105b opens into the casing 106 between the flanges 108 and 109. Pipes 110 and 111 also open into the casing 106 at points spaced endwise in opposite directions from the inlet from pipe 105b, so that the space between the flanges of the spool-shaped valve element 107 will connect the pipe 105b alternately to the pipes 110 and 111 as the element 107 is reciprocated in its casing. The ends of the casing 106 are connected by a pipe 112 to the tank 101. When the valve element 107 is in the position shown in full lines in Fig. 10, it will connect the pipe 105b to the pipe 111, and the latter is connected to the right-hand end of the casing 96. The pipe 110 is connected to the opposite end of the same casing 96 where it is vented by pipe 112. When the valve 107 is moved endwise of the casing 106 towards the opposite end of that casing, the flange 108 will pass the opening into the pipe 111, and thus cut off communication between the pipes 105b and 111, and the valve flange 109 will pass the opening into the pipe 110 and establish communication between the pipe 105b and the pipe 110 because the flange 109 will then be between the opening into pipes 110 and 112.

At the same time, the flange 108 will be disposed between the openings in the pipe 105b and 111, so that the latter pipe will be in communication with the pipe 112. Since the accumulator 102 delivers a constant supply of operating liquid under pressure to the pipe 105, it follows that this pressure will be transmitted to one or the other end of the valve casing 96, depending upon

the position of the valve element 107. The end of the valve casing 96 to which the pressure is not transmitted at any time will be connected with the pipe 112 leading to the tank 101. In the position of the parts shown in Fig. 10, liquid under pressure from the accumulator is conducted to the right-hand end of the valve casing 96. A rod 113 extends from the right-hand end of the valve element 97 toward the right-hand end of the cylinder and terminates in a pilot piston 114, disposed between the opening from pipe 100 and the adjacent end of the casing 96 into which the pipe 111 opens.

Similarly, a rod 115 extends from the opposite end of the valve element 97 toward the opposite end of the cylinder 96, and terminates in a pilot piston head 116 which reciprocates in that end of the casing 96 between the opening into pipe 100 and the end wall into which the pipe 110 opens. The pressure delivered to the right-hand end of the valve casing 96 acts on the piston head 116 to force the valve element 97 to the left, as shown by full lines in Fig. 10, and when this happens, the liquid under pressure delivered by the accumulator to the pipe 105 will be transmitted through the pipe 105a and the space of the spool valve 97 between the flanges 98 and 99 to the pipe 37, and thence to the left hand end of the cylinder 27. This pressure forces the piston 95 to the right and retracts the ram 26 to the right in Figs. 1 to 3 and 10. This retracts the yoke 25 and the injection rod 24 into the position shown in full lines in the drawings.

The parts remain in these positions until a rapid operation of the injection device is desired. The valve element 107 of the control valve 106 is provided with an operating rod 117 which extends outwardly through one end of the casing 106, Figs. 5, 8, 9 and 10, where it is connected to a latch rod 118 which forms a continuation thereof. The free end of the rod 118, Figs. 5 to 9, is pivotally connected by a pin 119 to a lever 120 pivoted at 121 on the base 10 of the machine. Thus, by stepping on the free end of the lever 120, it may be rocked from the position shown in full lines in Fig. 8 into the dotted line position shown in the same figure. When this occurs, the rods 117 and 118 will be moved endwise so as to shift the valve element 107 downwardly in Fig. 10 into a position in which the liquid from the accumulator will be transmitted through the pipe 105b to the pipe 110 instead of the pipe 111, and the pipe 111 will be vented through pipe 112. The accumulator pressure will then be applied to the left hand end of the casing 96 in Fig. 10, and the right hand end of the casing 96 will be vented to the pipe 112.

The accumulator liquid under pressure will thus pass through pipes 105b and 110, and acting on the pilot piston 116, will force the valve element 97 to the right in Fig. 10. The flange 98 of the element 97 will then be disposed between the inlet to pipe 37 and that of pipe 105a. This shuts off the transfer of accumulator liquid under pressure to the left-hand end of the cylinder 27. At the same time the flange 99 passes beyond the opening to pipe 36, and thus communication is established between the flanges 98 and 99 from pipe 105a to pipe 36. The pipe 37 is vented to the pipe 100, and thus the accumulator pressure now acting on the right hand end of the cylinder 27 will force the piston 95 to the left in Fig. 10, and through the yoke 25 and plunger 24 will force into the die sections any casting liquid previously placed in the chamber 75

19 through the opening 35. When the lever 120 is released, it will be returned to the position shown in Figs. 5, 8 and 10 in any suitable manner such as by the spring 122, Fig. 10. The valve element 97 will then be returned to the left hand position shown in Fig. 10 causing a retraction of piston 26, and the parts will remain in those positions until the operator again manipulates the lever 120 from the full to the dotted line position shown in Fig. 8. Liquid under pressure may be stored in the accumulator in any usual manner such as is now in common use, or it may be supplied to the accumulator through the pipe 123, and after the supply is stored therein the pipe 123 may be closed by a valve 124.

It will be observed that if an attendant through carelessness or accident should manipulate the lever 120 and cause an injection of the casting metal or material before the die sections 20 are fully closed with one another or held together with insufficient pressure, a serious accident might occur through the spilling of the casting material which is usually hot. Accordingly, provision is made of an interlocking safety 25 device to prevent any possibility of such an accident or operation. This safety device includes a cylinder 125 provided with a piston 126. A stem 127 extends outwardly through one end of the casing 125, the other end of the casing being 30 closed. A spring 128 within the casing 125 acts on the piston 126 to shift it further into the casing 125, as shown in Fig. 10. That closed end of the casing 125 is connected to the pipe 93, so that the piston 126 will always be subjected to 35 the pressure in the pipe 45 and hence to the pressure on the piston 14 at the closed end of the cylinder 13 but exteriorly of the flange 42. The rod 127 extends crosswise of the rod 117 and it is connected to a sliding latch block 129 having 40 intermediate of its ends a notch 130. The block 129 extends beneath the latch rod 118, as shown in Figs. 5 to 9, and is slidably guided by a groove 129a in the main base 10.

When the rods 117 and 127 are in their retracted positions shown in Fig. 10, a shoulder or 45 abutment 131 on the lower edge of the latch rod 118 will be engaged behind the sliding latch block 129, as shown in Figs. 6 and 8. It will thus be impossible to operate the lever 120, because 50 the engagement of the abutment or shoulder 131 with the side face of the rod 129 will prevent any such movement to initiate an injection of casting material into the die sections until the latch block 129 has first been moved endwise 55 until its notch 130 is brought into alignment with the shoulder or abutment 131, as shown in Figs. 7 and 9. This movement of the block 129 into the aligned position with the shoulder 131 occurs only after the increasing pressure on the 60 piston 14 has reached a predetermined minimum or adequate safe holding pressure by which the die sections are clamped together. Thus, until the die sections are clamped together with a safe holding pressure, one cannot manipulate the 65 lever 120 to cause an injection of casting material into the die sections. At the conclusion of a casting operation, when the platen 15 is retracted to separate the die sections, the pressure in the pipe 45 immediately falls, as hereinbefore explained, and when this happens the pressure 70 on the piston 126 decreases and the spring 128 returns the rod 127 to the position shown in full lines in Figs. 6, 8 and 10 where it again latches the rod 118 and valve element 107 in safe 75 position.

The operation of the casting press has been explained in connection with the description of the construction of the press and its controls. It will be noted that separate sources of pressure are utilized for holding the die sections closed and for operating the injection devices, and that an accumulator is preferably used to provide the pressure for causing the injection of the casting material. The accumulator pressure is relatively expensive, and a considerable saving is obtained by utilizing the pump as the source of pressure for the holding pressure. Notwithstanding the use of the pump, however, a rapid closing of the dies is possible and the holding pressure may be varied as necessary, depending upon the size of the cavities in the dies which determines, of course, the reaction pressures tending to separate the die sections.

Thus time and expense are saved by utilizing the adjustable delivery pump as the source of operating liquid for holding the die sections closed. It will also be noted that the work is loosened or ejected from the die sections automatically. The interlock between the two operating rams prevents any danger through premature operation of the device for injecting the casting material into the die sections. The tension of the spring 128 in the interlock which determines the pressure at which the casting material injection device can be operated, may be varied in any suitable manner, such as by inserting or removing shims 132 (Figs. 5 and 10) between the spring 128, and a removable block 133 fitted into the open end of the cylinder 125.

Because of the high pressures used to clamp the die sections together, it is desirable to tie the pressure head 11 to the ram base 12, and for this purpose strain rods 134 connect the pressure head and the ram base as usual in hydraulic presses. If the platen 15 is merely advanced sufficiently to close the dies and bring them in actual contact, and the liquid in the advancing ram then locked in the ram cylinder to prevent separation of the die sections during the casting operation, it is quite probable that the stretching of the strain rods 134 during the casting operation will allow a slight separation of the die sections with resulting formation of "flash" on the castings at the junction between the die sections. To reduce this "flash" to a very insignificant amount or to entirely eliminate it, we prefer to preload the strain rods 134 with sufficient pressure so that the additional stress on the strain rods during the casting operation through the reaction of the injected material or casting liquid will not cause any material separation of the die sections.

This preloading is accomplished by the arrangement herein described and illustrated for closing the die sections and holding them closed under the pressure from the continuously operating, variable delivery pump. The force necessary to cause the initial stretch of the strain rods 134 is much less than that necessary to stretch them a given amount after they have already been stretched to a considerable extent. By reason of this preloading of pressure on the die sections, the "flash" on the castings is substantially eliminated or reduced to a minimum.

It will be understood that various changes in the details and materials, which have been herein described and illustrated in order to explain the nature of the invention, may be made by those skilled in the art within the principle and scope of the invention, as expressed in the appended claims.

We claim:

1. In a pressure die-casting apparatus comprising a separable die mold, a hydraulic press to open and close the mold and hydraulically operated injecting means for delivering molten metal into the mold, a system to control the operation of said press and said injecting means having in combination separate hydraulic circuits for supplying working fluid to said press and said injecting means, respectively, independently actuated valve means in each circuit, a continuously acting variable delivery pump to operate the hydraulic press circuit, means responsive to the pressure in said press circuit to vary the rate of delivery of said pump, intermittently acting motive means including an accumulator connected to operate the metal injection circuit when permitted by said valve means in that circuit, a lock controlling the valve in the last mentioned circuit normally preventing operation thereof in a manner to cause injection of molten metal into the mold, and means responsive to a predetermined die closing pressure in the hydraulic press circuit to release said lock and permit operation of said valve means of the injecting circuit in a manner to allow operation of said metal injecting means.

2. In a pressure die-casting apparatus comprising a separable die mold, a hydraulic press to open and close the mold, and hydraulically operated injecting means for delivering molten metal into the mold, a system to control the operation of said press and said injecting means having, in combination, separate hydraulic circuits for supplying working fluid to said press and said injecting means, respectively, selectively operable valve means in the circuit of said injecting means for controlling the activity of said injecting means, means for supplying an operating fluid to said hydraulic press circuit to operate the same to close and open said mold and when said mold is closed to build up and maintain a predetermined holding pressure thereon, and means separate from said supplying means for delivering a separate operating fluid under constant pressure to said metal injection circuit to cause an operation of said injecting means and an injection of metal into said mold, whereby fluid pressure may be applied separately to said press and to said injecting means, a lock controlling said valve in the metal injection circuit and normally preventing operation of said valve into a position in which it permits an operation of said injecting means and thereby an injection of molten metal into the mold, and means responsive to a predetermined, safe die closing pressure in said hydraulic press circuit to unlock said valve for movement into a position to permit an operation of the metal injecting means.

3. In a pressure die-casting apparatus comprising a separable die mold, a hydraulic press to open and close the mold and hydraulically operated injecting means for delivering molten metal into the mold, a system to control the operation of said press and said injecting means having in combination separate hydraulic circuits for supplying working fluid to said press and said injecting means, respectively, a valve in said circuit of said injecting means, a pump device connected to the hydraulic press circuit to deliver operating fluid thereto and first close the die mold and then build up and maintain a predetermined holding pressure thereon, intermittently acting motive means connected to the met-

al injection circuit for supplying thereto an operating fluid under constant pressure throughout the operation of said injecting means and separate from said holding circuit, a lock controlling said valve means and normally preventing operation thereof into a position to permit an injection of molten metal into the mold, and means responsive to a predetermined closure holding pressure on the mold in the hydraulic press circuit to unlock said valve means for movement into a position in which it permits an operation of the metal injecting means.

4. In a pressure die-casting apparatus comprising a separable die mold, a hydraulic press to open and close the mold and hydraulically operated injecting means for delivering molten metal into the mold, a system to control the operation of said press and said injecting means having in combination separate hydraulic circuits for supplying working fluid to said press and said injecting means, respectively, means controlling the activity of said press circuit and thereby controlling the opening and closing of said mold, a valve in said metal injection circuit for controlling the activity of said injecting means, pumping means connected to said press circuit to supply an operating fluid thereto, close said die mold and then build up and maintain a predetermined closing pressure thereon, a separate, intermittently acting, motive means for supplying an operating fluid under constant pressure throughout operation of said metal injection circuit to cause an operation of said injecting means when permitted by said valve, a lock controlling said valve and normally preventing operation thereof in a manner to cause injection of molten metal into said mold, and means responsive to a predetermined holding pressure on said mold in the hydraulic press circuit for operating said lock to release said valve for operation in a manner to cause a casting operation of said metal injection means.

5. In a pressure die-casting apparatus comprising a separable die mold, a hydraulic press to open and close the mold and hydraulically operated injecting means for delivering molten metal into the mold, a system to control the operation of said press and said injecting means having in combination separate hydraulic circuits for supplying working fluid to said press and said injecting means, respectively, a valve in said circuit for said injecting means, a continuously acting, variable delivery pump connected to said press circuit for operating the same to close the die mold and then build up and maintain a predetermined closing pressure thereon, means responsive to the closing pressure in said press for varying the rate of delivery of said pump, intermittently acting, motive means connected to the metal injection circuit for supplying thereto an operating fluid at a constant pressure at all rates of delivery and separately from the holding pressure on said mold, a lock controlling said valve and normally preventing operation thereof in a manner to cause injection of molten metal into the mold, and means responsive to a predetermined mold closing pressure in the hydraulic press circuit for operating said lock to release said valve and permit operation of the latter in a manner to permit an operation of the metal injecting means.
